CLAIM

The ornamental design for a pocket knife, as shown and described.

DESCRIPTION

FIG. 1 is a left perspective view of a pocket knife embodying the new design with the blade deployed;

FIG. 2 is a right side elevation view of the pocket knife with the blade deployed;

FIG. 3 is a left side elevation view of the pocket knife with the blade deployed;

FIG. 4 is a top plan view of the pocket knife with the blade deployed;

FIG. 5 is a bottom plan view of the pocket knife with the blade deployed;

FIG. 6 is a front side elevation view of the pocket knife with the blade retracted;

FIG. 7 is a rear side elevation view of the pocket knife with the blade retracted;

FIG. 8 is a right side elevation view of the pocket knife with the blade retracted;

FIG. 9 is a left side elevation view of the pocket knife with the blade retracted;

FIG. 10 is a top plan view of the pocket knife with the blade retracted; and,

FIG. 11 is a bottom plan view of the pocket knife with the blade retracted.

The broken lines in the drawings represent portions of the pocket knife that form no part of the claimed design.

1 Claim, 10 Drawing Sheets
